UNITED STATES PATENT OFFICE.

JAMES WEST, OF BROOKLYN, NEW YORK.

DESIGN FOR A FONT OF COMBINATION TYPE ORNAMENTS.

SPECIFICATION forming part of Design No. 16,921, dated September 28, 1886.

Application filed March 13, 1886. Serial No. 195,167. Term of patent 31 years.

To all whom it may concern:

Be it known that I, JAMES WEST, of Brooklyn, county of Kings, and State of New York, have invented a new and original Design for a Font of Combination Type Ornament, of which the following is a full, clear, and exact description, reference being had to the accompanying specimen or impression, making part of this specification, which is an exact representation of my design.

This design relates to fonts of combination type ornaments, as shown in the accompanying specimen.

The design consists of the parts 1 to 17, inclusive, 1 being spiral ornaments; 2, border of palmetto-leaves; 3, angle palmetto-leaf; 4, flowers and spirals; 5, a Greek ovolo ornament; 6, a Greek ovolo corner ornament; 7, crossed fancy lines; 8, circles with ornamental circles; 9, rectangular figure with concave sides and cross ornaments; 10, a piece of body-shading; 11, leaf ornaments; 12, rectangular ornament formed of overlapping bars; 13, body-shading ornamented with dots, one at the middle of each side; 14, body-shading or-

nament with dots, one at each corner, the body-shading lines forming right angles; 15, an ornament consisting of one square placed within the other, the corners of the middle square being at the middles of the sides of the outer square; 16, an oblong ornament formed of cross-bands and ornaments between the end angles; 17, a corner piece for 16.

It is evident that one or the other of the ornaments may be omitted without in any way injuring the design.

What I claim as my invention, and desire to secure by Letters Patent, is--

The design for a font of combination type ornaments, as herein shown and described, the same consisting of the ornaments 1 to 17, inclusive.

In testimony that I claim the foregoing as my invention I have signed it this 12th day of March, 1886.

JAMES WEST.
